UNITED STATES PATENT OFFICE.

EDWIN R. STORM, OF NEW YORK, N. Y.

ROTARY PRINTING-PRESS.

1,139,314.

Specification of Letters Patent. Patented May 11, 1915.

Application filed September 10, 1907. Serial No. 392,146.

To all whom it may concern:

Be it known that I, EDWIN R. STORM, a citizen of the United States, residing at New York, in the county of New York and State of New York, have invented a new and useful Rotary Printing-Press, of which the following is a specification.

My invention relates to improvements in presses in which the printing types are placed upon a rotary cylinder; and the objects of my improvement are, first, to provide a cylindrical type holder and means for quickly and firmly holding the types to the cylinder or releasing them therefrom; second, to provide a means for holding the cylinder in the machine or for removing it therefrom for purposes of either cleaning or distributing the type; third, to provide a means for holding the material to receive the type impressions against the type faces; fourth, to provide a means for automatically inking the type faces before each impression; and, fifth, to provide a means for automatically feeding the sheets intended to receive the impressions to the type. I attain these objects by the mechanism whose preferred form is shown in the accompanying drawings, in which—

Figure 1 is an end view of the complete machine; Fig. 2 is a side elevation of the complete machine; Fig. 3 is an enlarged view of the rod which holds the type cylinder in position; Fig. 4 is an end view of the same rod; Fig. 5 is a sectional view of the type cylinder showing the cylinder upon which the type rest, the end-pieces which form sides of the chase, the head-piece which forms the ends of the chase, and the hubs formed on the end-pieces; Fig. 6 is a sectional view of the type cylinder taken at right angles to the axis, and showing the cylinder upon which the type rest, the novel construction of the type which enables them to be locked to the cylinder, the retaining bars which lock the type to the cylinder, the end-pieces which form the sides of the chase, the head-piece which forms the ends of the chase, and the screws for compressing the lines of type; Fig. 7 is a perspective view of a type; Fig. 8 is a side view of one of the feed-wheels, showing the crank and eccentric for the automatic feed in dotted lines; Fig. 9 is a sectional view of the same wheel, showing the half view of the same feed-wheel, showing the half hub for cen-

tering and rotating the type cylinder, the crank and eccentric for the automatic feed, and the hollow shaft; Fig. 10 is an enlarged view of the locking lever which prevents the rod shown in Fig. 3 from jarring out of place; Fig. 11 is a sectional view of the automatic feed, showing the pitman, pump, suction-plate, roller and holding-sleeve; Fig. 12 is a side view of a locking-bar, showing the projecting ends; Fig. 13 is a side view of a spring quoin; Fig. 14 is an edge view of the same spring-quoin; Fig. 15 is a view of a holder for use in printing pieces whose width is less than the distance between the feed-wheels.

Similar numerals refer to similar parts throughout the several views.

The frame of the machine, of any desired form, is shown as having a bed 1, and uprights 2, 2'. See Figs. 1 and 2. The uprights 2, 2' are formed with the boxes 3, 3' and 4, 4', the raised portions 5, 5' and 6, 6' and the oil-wells 7, 7', and are pierced with the threaded holes 8, 8' and 9. To the boxes 3, 3' are fitted the steps 10, 10' held to place by the caps 11, 11' and cap-screws 12, 12'. To the boxes 4, 4' are fitted the steps 13, 13' held to place by the caps 14, 14' and the cap-screws 15, 15'. See Figs. 1 and 2. To the steps 10, 10' are fitted the journals 16, 16' of the impression roller 17. The roller 17 is covered with any suitable resilient material 18. To the steps 13, 13' are fitted the journals 19, 19' of the feed-wheels 20, 20'. The journal 19 and feed-wheel 20 are pierced with a cylindrical hole 21 whose axis coincides with the axis of the journal and wheel, forming a hollow mandrel or portion of a divided hollow shaft, to which is fitted the rod 22. See Figs. 1, 2, 3 and 9. On one side of each feed-wheel 20, 20' is formed a semi-cylindrical hub 23, 23' and an inclined face 24, 24'. The face of the wheel is formed of a suitable yielding portion 25. See Figs. 8 and 9. The journal 19 of the feed-wheel 20 is extended to receive the operating crank 26, and the journal 19' of the feed-wheel 20' is extended to receive the eccentric 27 and crank 28. See Figs. 1 and 9. The rod or locking core 22 is formed with a knob or handle 29 at one end and is provided with a recessed portion 30 at the opposite end, see Figs. 1, 3 and 4. To the rod 22 is fitted the type-cylinder 31, which is preferably

formed with a cylindrical body 32, having end-piece 33 and end-disk 34. The three parts are shown in the drawing as formed separately and held together by the screws 35. The end-piece 33 is formed with the recess 36 and the semi-cylindrical hub 37, and is furnished with the bushing 38. The end-disk 34 is furnished with the bushing 39 formed with a retaining shoulder 40. On the bushing 40 is rotatably mounted the end-piece 41 formed with the recess 42, similar to the recess 36, the semi-cylindrical hub 43, the channel 44, cut through the rim communicating with the recess 42, and the hole 45 formed to hold the pin 46. Secured to the cylindrical body 32 by the screws 47, 48 is the head-piece 49, formed with the rabbet 49' and holding in the threaded holes 50 the tightening-screws 51. The hole 52, in the end of the head-piece 49, is formed to receive the end of the pin 46.

The type 53 are formed with a type-body whose essential feature is a portion adapted to engage the retaining-bars 54. In the drawings the body is shown in its preferred form with a radial face 55, an inclined face 56 and a projecting portion 57. See Figs. 6 and 7. In Fig. 6, placed against the front face of the head-piece 49, is shown a type 30 having a projecting portion 55' adapted to fit the rabbet 49'. If desired this projection could be formed on all the type, and would be required on the corresponding face of a large block of type, or an illustration, to 35 hold it to the type cylinder.

The retaining-bars 54 are formed with recessed ends leaving the projecting portions 58 and 59, as shown in Fig. 12. The projecting portions 58 and 59 are fitted to the recesses 36 and 42. The channel 44 is 40 formed of a width sufficient to admit the passage of the portion 59.

The operating crank 26, secured to the extension of the journal 19, is provided with a lever 60 fulcrumed on the screw 61 and formed with an end 62 adapted to reach through the slot 63 in the hub of the crank and journal extension and engage with the recess 30 in the rod 22. The lever 60 is also 50 provided with a thumb-piece 64 and a spring 65, as shown in Figs. 1, 2 and 10.

The threaded holes 8, 8' are adapted to hold the screws 66, 66' which are fitted to holes in the rock-frame 67. The rock-frame 55 67, formed as indicated is provided with holes 68, 68', to which are fitted the journals 69, 69' of the inking roller 70. Secured to the raised portions 5, 5' by the screws 71, 71' are the leaf-springs 72, 72' which bear 60 against the formed ends 73, of the rock-frame 67. See Figs. 1 and 2.

To the hole 9 is fitted the screw 74 upon which is mounted the formed arm 75, one end of which is adapted to press upon and 65 be controlled by the cam 27. See Figs. 1

and 2. The outward movement of the arm 75 is limited by the pin 76 coming in engagement with the projection 77, as shown in Fig. 2. The cam 27, formed to push, or hold, the arm 75 away from the axis of rotation of the cam during the greater portion of the revolution and to allow it quickly to approach the axis at a predetermined point of revolution, is, with the crank 28, rigidly fixed to the extension of the journal 19'. In the crank 28 is fixed the pin 78 which enters the hole 79 of the pitman 80. The pitman 80 is held upon the pin by the retaining screw 81. See Figs. 2 and 9. The pitman 80 is made telescopic by means of the sleeve 82, the two portions being held together by the helical spring 83 which has one end attached to the eye 84 in the pitman 80 and the other end attached to the eye 85 in the head 86 of the sleeve 82. On the sleeve 82 is formed the strike-piece 87 which engages with the arm 75. The head 86 is formed to connect, by means of the pin 88, with the piston-rod 89 of the pump 90, whose cylindrical sides serve as a barrel and whose ends 91 and 92 are made to facilitate the egress of air from the barrel and to obstruct its entrance to the barrel. This is accomplished in the end 91 by forming the gland 93 of a suitable flexible material and holding its larger circumference to place by the disk 94 and nut 95, and in the end 92, by piercing the end with holes 96, 96' and covering them with the flap valves 97, 97', which are held to place by passing the strip forming the valves 100 through the slot 98 in the stem 99. The stem 99 connects the end 92 with the holding-sleeve 100. The holding sleeve 100, provided with the arm 101 in which is fitted the roller 102, is fitted to the post 103, which is secured to the table 104. The piston-rod 89, formed as a tube is furnished with a piston having two formed disks 105, 106 of a suitable flexible material adapted to act as a piston packing; a disk 107, attached to the piston rod; a sleeve 108, serving to separate the two formed disks 105 and 106; and a retaining-screw 109. Holes 110, 111 pass through the sleeve 108 and the piston-rod 89 allowing free communication between the space 112 and the bore of the piston-rod. The piston-rod 89 is formed with the communicating hollow arm 113 which terminates in a suction-plate 114. See Figs. 1, 2 and 11.

To the raised portions 6, 6', is secured the 120 curved plate 115. See Figs. 1 and 2. The bed 1 is shown mounted on a chest of drawers 116 which may serve as type cases. To the chest of drawers 116 is secured the socket 117, to which is sildably fitted the standard 118. The standard 118 is secured to the table 104. The table 104 is secured at any desired position by means of the thumb-screw 119. To the table 104 are secured the guide-plates 120 and 121 and 130

125

to the top of the chest of drawers 116 is secured the guide-plate 122, see Figs. 1 and 2. Where the types do not fill the lines a spring quad 123, formed of thin spring metal bent as indicated in Fig. 14 and of form shown in Fig. 13 is inserted. The last retaining-bar 124 is made heavier than the others to distribute the pressure of the tightening-screws 51, and, for convenience in designating it, is called the pressure-bar. It is shown in Fig. 6 and is formed with projecting portions similar to the projecting portions 58 and 59 of the retaining-bars 54 and which are adapted to pass through the channel 44.

The operation of the machine is as follows: Rotate the rock-shaft, 67, by means of the cylindrical portion 125, or its spherical ends, which may be used as a handle; until it is approximately parallel with the bed 1. This removes the ink-roller, 70, from proximity to the type-cylinder, 31. Depress the thumb-piece 64 of the lever 60, thus raising the end 62 from the recess 25 in the rod 22. By means of the handle 29 remove the rod 22 from the hollow journals, or mandrels, 19, 19'. The type cylinder may now be lifted from place, after which the end of the pin 46 may be removed from the hole 52 and the end-piece 41 rotated until the channel 44 is in front of the head-piece 49. Set the first line of type against the face of the head-piece, as shown in Fig. 6, inserting a spring quad 123, if necessary, to keep the type from moving endwise of the line. Place the projecting portion 58 of the retaining-bar 54 in the recess 36 of the end-piece 33, pass the projecting portion 59 through the channel 44 in the rim of the end-piece 41 into the recess 42, move the bar until it rests against and holds the type to place. Then set the succeeding lines of type in a similar manner, rotating the end-piece 41 so as to keep the channel 44 in advance of the lines of type. If illustrations, or solid blocks of type are to be used secure them to the type cylinder by placing the projecting portions 55', which must be formed on any large blocks, in the rabbet 49', if they are next to the head-piece 49, or under a retaining bar 54, and hold the forward edges with the retaining-bars in a manner similar to the types. When the last row of types has been placed upon the type cylinder the end-piece 41 is rotated until the hole 45 registers with the hole 52 when the pin 46 is pushed into the hole 52 preventing rotation of the end-piece 41, then the pressure-bar 124 is pressed against the types by the tightening-screws 51 pressing the several lines of types together, thus locking the types securely in place and to the cylinder. If desired the type could be placed upon the cylinder without removing it from the machine. The type-cylinder is then

placed in the machine with the end of the bushing 38 resting in the semi-cylindrical hub 23', and one end of the bushing 39 resting in the semi-cylindrical hub 23, in such a manner that the semi-cylindrical hubs 37 70 and 43 rest upon the semi-cylindrical hubs 23 and 23' forming circular hubs. This centers, or alines, the cylinder, and the rod 22 may then be inserted in the hole 21, the thumb-piece 64 of the lever 60 depressed, the end 62 raised, the rod 22 moved until the recess 30 registers with the slot 63. Upon releasing the thumb-piece the end 62 moves into the recess 30 thus locking the rod and cylinder in place. The engagement of the semi-cylindrical hubs locks the type-cylinder to the feed wheels so they must rotate as a unit. The rock-frame 67 is then rotated back to its normal position, when the leaf-springs 72, 72' bearing against the formed ends 73, 81 hold the ink-roller 70 against the type faces so that upon rotation of the type-cylinder the printing faces of the types receive a film of ink. To place the printing sheets in position, raise the holding sleeve 100 and with it the roller 102, the pump 90 and the suction-plate 114, removing the holding-sleeve 100 from the post 103 if necessary, and place on the table 104 the material to receive the impressions—usually sheets of paper—in a pile having a side resting against the guide plate 121 and an end against the guide plate 120, then lower the holding-sleeve 100 on the post 103 until the roller 102 and the suction-plate 114 rests on the top of the pile. The press is now ready to print.

Upon turning the operating crank 26, it rotates the feed-wheels, 20, 20', the type-cylinder 31, the cam 27, and crank 28. The type-cylinder 31 rotates the ink-roller 70; 105 the feed-wheels 20, 20' rotate the impression roller 17, the cam 27 bears against the end of the arm 75; the crank 28 operates the pitman 80 which draws the piston-rod 89 and suction-plate 114 toward the type-cylinder 31, this loosens the gland 93 permitting the air in that end of the pump 90 to escape, closes the valves 97, 97' which rarifies the air in that end of the pump 90. The rarifying of the air in that portion of the pump 90 which contains the end 92, causes the air in the piston-rod 89 to pass through the holes 110, 111 contracting the outer circumference of the formed disk 105. The tendency of the air to pass through the hole in the suction-plate 114 and piston-rod 89 raises and holds the top sheet of paper to the suction-plate. As the piston is brought forward the sheet of paper is carried with it. The curved plate 115 guarding the sheet from smearing on the type-cylinder. As the crank 26 continues to rotate, the strike-piece 87 is brought to bear against the arm 75, which checks the forward movement of the sleeve 82, piston 89 and suction-plate 114 130

and with them the advancing sheet. The continued movement of the pitman 80 is taken up by extending the spring 83. The retarding of the sleeve, piston-rod, and suction-plate is arranged to occur when the forward edge of the sheet of paper is about to be gripped by the roller 70 and the feed-wheels 20, 20'. At a predetermined point in its rotation, the cam 27 permits the arm 75 to move toward the journal 19'. The extended spring 83 contracts, moving the sleeve 82 forward. The sleeve carries forward the piston-rod 89 and suction-plate 114. The suction-plate carries the sheet forward entering its forward edge between the roller 70 and the feed-wheels 20, 20'. Continued rotation of the crank 26 causes the sheet to be gripped by the feed-wheels and carried through the machine. The impression roller 17 holding it against the feed-wheels and the inked type-faces. After delivering the sheet to the roller and feed-wheels, the suction-plate 114 is moved backward by the sleeve 82 and pitman 80, this expands the formed disk 105; opens the valves 97, 97'; contracts the formed disk 106 and gland 93; rarifies the air in the end 91 of the pump 90; and causes the sheet to press against the suction-plate. After the sheet which is passing through the machine leaves the suction-plate, the next underlying sheet is drawn up and held against the suction-plate, and, if it has been moved forward by the preceding sheet, is now returned to its position against the guide-plates 120 and 121. Continued rotation of the crank 26 repeats the operations indefinitely.

The arm 75 is formed so the strike-piece 87 will always be stopped at approximately the same distance from the point of tangency of the impression roller 70 and feed-wheels 20, 20', whether the suction-plate be delivered the first, last, or any intermediate sheet of the pile.

The holder 126, shown in Fig. 15 is formed of any thin material folded as indicated, and is for use in printing sheets that are narrower than the space between the feed-wheels. It is used by inserting an edge of the sheet to receive the impression in the fold 127 then passing the holder 126, with the sheet thereon, between the impression roller and the type cylinder. The width of the holder 126 should be such that the end 127 will pass under one feed-wheel while the end 128 passes under the other feed-wheel.

For purposes of washing, or cleansing, and distributing the type, the type-cylinder can be removed from the machine by removing the rod 22, as previously explained. I have shown the movable end-piece 41 as rotating to admit the holding bars, as the preferred form, but the projecting ends 59 could be admitted by sliding the movable

end-piece along the bushing 39, which would require to be made enough longer to admit the movement. Where the operator has power a belt or gear wheel could be substituted for the operating-crank 26. If desired the automatic feed can be detached and the machine fed by hand.

Having described the machine I claim as my invention and desire to secure by Letters Patent,—

1. In a rotary printing press, a type-cylinder having a cylindrical type-bed and formed with one end of a diameter smaller than the diameter of the type-bed, and the other end of a diameter greater than the type-bed; and an end piece of a diameter greater than the diameter of the type-bed rotatably mounted on the said smaller end.

2. In a rotary printing press, a type-cylinder having a cylindrical type-bed and formed with one end of the diameter of the type-bed and the other end with a recessed portion extending beyond the type-bed; a sleeve on the smaller end of the type-cylinder formed with its axis coincident with the axis of the said type cylinder; and a recessed end-piece of a diameter greater than the diameter of the said type-bed rotatably mounted on the said sleeve.

3. In a rotary printing-press; a type cylinder having a cylindrical body; a fixed end-piece extending beyond the cylindrical body and having an annular recess in the extended portion; an end-disk fitted in one end of the cylindrical body; a rotatable end-piece extending beyond the said cylindrical body and having an annular recess in the extended portion and a channel communicating with the said recess; sections of a hollow shaft on which the cylinder is mounted; and a rod fitting the hollow sections.

4. In a rotary printing-press; a type cylinder having a cylindrical body perforated by an axial hole; a fixed end-piece on one end of the type cylinder extending beyond the cylindrical body and having an axial hole and an annular recess in the extended portion; an end-disk of approximately the diameter of the type cylinder terminating the opposite end of the type cylinder and provided with an axial hole; sections of a hollow shaft fixed in the end-piece and end-disk; a rotatable end-piece mounted on the section of the hollow shaft in the end-disk; an extended portion on the rotatable end-piece having an annular recess and a channel communicating with the said recess; and a locking-rod filling the sections of the hollow shaft.

5. In a rotary printing-press; a type cylinder having a cylindrical body; a head-piece secured to the type-cylinder; a fixed end-piece extending beyond the cylindrical body; a rotatable end-piece extending beyond the cylindrical body; semi-cylindrical

- hubs on the end-pieces; sections of a hollow shaft fitted to the cylinder; and a rod filling the sections of the hollow shaft.
6. In a rotary printing-press; a type-cylinder having a cylindrical body perforated by an axial hole; a fixed end-piece extending beyond the said cylindrical body and provided with an annular recess and an axial hole; an end-disk of approximately the same diameter as the cylindrical body, and perforated by an axial hole; bushings in the holes of the end-piece and end-disk; a collar on the bushing in the end-disk; an end-piece extending beyond the cylindrical body rotatably mounted on the said collared bushing and provided with an annular recess and a channel communicating with the said recess; a head-piece secured to the type-cylinder and semi-cylindrical hubs on the end-pieces.
7. In a rotary printing-press; a type cylinder having a cylindrical body adapted to receive the type; end-pieces on the type-cylinder extending beyond the cylindrical body; type having a side inclined to the printing-face so as to form a radial line when set; a retaining bar having a face formed so as to be a radial line when in use; a projection on the said type adapted to engage with the said retaining bar; hubs on the said end-pieces having an axial hole; cooperative hubs provided with an axial hole and mounted in bearings in a frame, and a locking rod adapted to fit and be held in the said axial holes.
8. In a rotary printing-press; a type-cylinder having a cylindrical body adapted to receive the type; end-pieces on the type-cylinder extending beyond the cylindrical body, adapted to act in conjunction with the types and quads of each line to prevent the types or quads adjacent to the said end pieces from moving sidewise, and provided with annular recesses in the extended portions; types on the type cylinder, having two sides approximately parallel, a side approximately perpendicular to the plane of the face of the character end, and a side inclined to the plane of the face of the character end; type-retaining bars; projections on the ends of the said types engaging with the said type-retaining bars; and formed hubs on the said end-pieces.
9. In a rotary printing-press; a type cylinder having a cylindrical body adapted to receive the type; end-pieces on the type cylinder extending beyond the cylindrical body adapted to form a side support for the end types of each line, and having an annular recess in the extended portion of each end-piece; types having the side at the top of the character inclined to the plane of the face of the character on the type-cylinder; type retaining bars; projections on the retaining bars fitted to the said annular recesses; projec-
- tions on the ends of the types engaging with the retaining bars; a head-piece secured to the said type cylinder; tightening screws in the said head-piece; a pressure bar; a shaft upon which the said type-cylinder is mounted and bearings in a frame.
10. In a rotary printing-press; a type cylinder having a cylindrical body adapted to receive the type; end-pieces on the type cylinder extending beyond the cylindrical body adapted to form a side support for the types at the end of each line; a quad having a body in the form of a double leaf spring, each spring being provided with a side approximately parallel to the bottom of the quad, a side approximately radial when set on the type-cylinder, and a side inclined to the bottom of the quad; type retaining bars; a projection on the quad near the bottom, adapted to engage with the type retaining bars; a shaft on which the said cylinder is mounted; a frame, and bearings in the frame.
11. In a rotary printing-press; a type-cylinder having a cylindrical body adapted to receive the type; end-pieces on the type cylinder extending beyond the cylindrical body adapted to form a side support for the types at the ends of each line; types on the cylinder; a quad having a reentrant side and a projection at the termination of the reentrant side; and formed as a leaf spring and adapted to take up small differences between the length of the type line and the space between the extended end-pieces; a shaft upon which the type cylinder is mounted; a frame, and bearings in the frame.
12. In a rotary printing-press; a type cylinder fitted with sections of a hollow shaft; feed-wheels mounted on sections of a hollow shaft; journals formed on the sections of the hollow shaft in the feed-wheels; interlocking hubs on the said cylinder and feed-wheels; and a locking-rod fitted to the hole and uniting the sections of the hollow shaft.
13. In a rotary printing-press, a type-cylinder provided with hubs formed with a projecting portion and having an axial hole through the said cylinder and hubs; feed-wheels provided with hubs formed to supplement the hubs on the type cylinder and having an axial hole through the said feed-wheels and hubs; and a rod fitted to the axial hole in the cylinder and feed-wheels.
14. In a rotary printing-press; a type cylinder having semi-cylindrical hubs and provided with an axial hole through the said hubs and cylinder; bushings in the said hole; feed-wheels having axial holes; and hubs on the feed-wheels formed to supplement the said hubs on the type cylinder, and provided with axial holes recessed to receive the said bushings.
15. In a rotary printing-press, a type cylinder having semi-cylindrical hubs and pro-

- vided with an axial hole through the said hubs and cylinder; bushings in the said hole; feed-wheels having axial holes; hubs on the feed-wheels formed to supplement the said hubs on the type-cylinder, and provided with axial holes recessed to receive the said bushings; and a rod fitting all the said holes.
16. In a rotary printing-press; bearings in a frame; sections of a hollow shaft journaled in the bearings; feed-wheels mounted on the sections of the hollow shaft; a type cylinder adapted to work between the feed-wheels; interlocking hubs on the said feed-wheels and cylinder; an extension on one of the sections of the hollow shaft and an operating crank secured to the extension.
17. In a rotary printing-press, a hollow type cylinder fitted with sections of a hollow shaft; feed-wheels mounted on sections of a hollow shaft in bearings; a rod fitted to the hole in the sections of the hollow shaft; and interlocking hubs on the said cylinder and feed-wheels.
18. In a rotary printing press, portions of a hollow sectional shaft journaled in bearings in a frame; feed-wheels mounted on the sections; a yielding surface on the face of the feed wheels, a type cylinder mounted on portions of a hollow sectional shaft carried by the feed-wheels; and a locking rod in the hollow sectional shaft.
19. In a rotary printing-press, a feed-wheel; a journal on the feed-wheel, provided with an axial hole; a bearing fitted to the journal, in a frame; an extension on the journal; and an operating crank on the said extension.
20. In a rotary printing-press, a frame; bearings in the frame; sections of a hollow shaft journaled in the bearings; feed-wheels mounted on the said sections; a type cylinder provided with hubs and having an axial hole through the cylinder and hubs; hubs on the feed-wheels formed to supplement the hubs on the type cylinder; a rod fitted to the hole in the sections of the hollow shaft and the axial holes in the hubs of the cylinder; and an operating crank attached to one of the sections of the hollow shaft.
21. In a rotary printing-press; a type cylinder having an axial hole fitted with sections of a hollow shaft; feed-wheels on sections of a hollow shaft mounted in bearings; an operating crank attached to one of the said sections; a lever fulcrumed in the crank; a spring secured to the lever and bearing on a projection of the crank; a rod fitted to the hole in the sections of the hollow shaft and having a recess adapted to receive one end of the lever; and a handle on the rod.
22. In a rotary printing-press; portions of a hollow sectional shaft journaled in bearings in a frame; feed-wheels mounted on the sections; a type cylinder mounted on portions of a hollow sectional shaft car-

ried by the feed-wheels; a locking-rod in the hollow sectional shaft; and a roller bearing against the said feed-wheels and type-cylinder.

23. In a rotary printing-press; portions 70 of a hollow sectional shaft journaled in bearings in a frame; feed-wheels mounted on the sections; a type cylinder mounted on portions of a hollow sectional shaft carried by the feed-wheels; a locking-rod in the 75 hollow sectional shaft; an impression roller bearing against the said feed-wheels and type cylinder; and a resilient surface on the face of the said roller.

24. In a rotary printing-press; portions 80 of a hollow sectional shaft journaled in bearings in a frame; feed-wheels mounted on the sections; a type cylinder mounted on portions of a hollow sectional shaft carried by the feed-wheels; a locking-rod in the hollow 85 sectional shaft; an impression roller bearing against the feed-wheels and type cylinder; and a plate guarding the type cylinder.

25. In a rotary printing-press; portions 90 of a hollow sectional shaft journaled in bearings in a frame; feed-wheels mounted on the sections; a type cylinder mounted on portions of a hollow sectional shaft carried by the feed-wheels; a locking-rod fitted to the hollow sectional shaft; an impression 95 roller bearing against the feed-wheels and type cylinder; and an inking-roller bearing on the type cylinder.

26. In a rotary printing-press; portions 100 of a hollow sectional shaft journaled in bearings in a frame; feed wheels mounted on the sections; a type cylinder mounted on portions of a hollow sectional shaft carried by the feed-wheels; a locking-rod fitted to the portions of the hollow sectional shaft; 105 an impression roller bearing against the feed wheels and type-cylinder; bearings for the impression roller; and a frame carrying all of the said bearings.

27. In a rotary printing press, portions 110 of a hollow sectional shaft journaled in bearings in a frame; feed-wheels mounted on the sections; a type cylinder mounted on portions of a hollow sectional shaft carried by the feed-wheels; a locking-rod fitted to 115 the hole in the portions of the hollow sectional shaft; an impression roller bearing against the feed-wheels and type cylinder; a frame carrying all of the said bearings; a rock-frame mounted on the said frame; and 120 a shaft mounted in the rock-frame.

28. In a rotary printing press, portions of a hollow sectional shaft journaled in bearings; feed-wheels mounted on the sections; a type cylinder mounted on portions of a 125 hollow sectional shaft carried by the feed-wheels; an impression roller bearing against the feed-wheels and type cylinder; bearings for the impression roller; a frame carrying all of the said bearings; a rock-frame; a 130

shaft mounted in the rock-frame; and a handle on the rock-frame.

29. In a rotary printing press, portions of a hollow sectional shaft journaled in bearings; feed-wheels mounted on the sections; a type-cylinder mounted on portions of a hollow sectional shaft carried by the feed-wheels; an impression roller bearing against the feed-wheels and type cylinder; bearings for the impression roller; a frame carrying all of the said bearings; a rock-frame; a shaft mounted in the rock-frame; and springs holding the rock-frame in an upright position.

15 30. In a rotary printing press, portions of a hollow sectional shaft journaled in bearings; feed-wheels mounted on the sections; a type cylinder mounted on portions of a hollow sectional shaft carried by the feed-wheels; 20 a locking-rod fitted in the hollow sectional shaft; a frame carrying all of the bearings; a rock-frame in bearings; a shaft mounted in the rock-frame; and springs adapted to hold the rock-frame in an upright position or in a prostrate position.

25 31. In a rotary printing-press; the combination of a frame; bearings in the frame; portions of a hollow sectional shaft journaled in the bearings; feed-wheels on the said portions; a type cylinder mounted on sections of a hollow shaft and carried by the feed-wheels; a locking-rod uniting the sections of the hollow shaft; an impression roller; an inking roller; and an operating crank.

35 32. In a rotary printing-press; the combination of a frame; bearings in the frame; portions of a hollow sectional shaft journaled in the bearings; feed-wheels on the said portions; a type cylinder mounted on sections of a hollow shaft and carried by the feed-wheels; a locking-rod uniting the sections of the hollow shaft; an impression roller; a guard plate; a guide plate; and a feeding device substantially as described.

40 33. In a rotary printing press, a type cylinder having a hollow cylindrical type-bed; a fixed end-piece secured to the type-bed and provided with an axial hole; a hub on the fixed end-piece, provided with an axial hole; a circular portion of the fixed end-piece formed to extend from the cylindrical surface of the type-bed to a predetermined point beyond it; and provided with an annular recess; a fixed end-disk of approximately the same diameter as the said type-bed, secured to the type-bed and provided with an axial hole; and a hub on the fixed end-disk provided with an axial hole.

45 34. In a rotary printing press, a type cylinder having a hollow cylindrical type-bed; a cylindrical fixed end-piece formed of a diameter greater than the diameter of the type-bed, provided with an annular recess in the portion extending beyond the cylindrical

surface of the type-bed, perforated by an axial hole and secured to the type-bed; a hub on the fixed end-piece, provided with an axial hole; an end disk of approximately the same diameter as the type-bed perforated by an axial hole and secured to the type-bed; a hub on the end disk provided with an axial hole; and a cylindrical end-piece extending beyond the cylindrical type-bed, provided with an annular recess in the portion extending beyond the cylindrical surface of the type-bed, furnished with a channel extending from the perimeter to the annular recess, and revolvably mounted on the hub of said end disk.

50 35. In a rotary printing-press; a type cylinder having a cylindrical body; an end-piece rotatably mounted on the cylinder, formed with a portion of a greater diameter than the diameter of the cylinder and provided with a hole for a lock-pin; a head-piece secured to the type cylinder and provided with a hole registering with the hole in the rotatable end-pieces; a pin adapted to be held in both of the said holes; a shaft on which the cylinder is mounted and bearings adapted to receive the shaft.

36. In a rotary printing press; a type cylinder having a cylindrical body provided with an axial hole; end-pieces on the cylinder extending beyond the said cylindrical body and perforated with axial holes to receive a locking-rod, portions of a divided hollow shaft secured to the end-pieces; bearings in a frame and a locking-rod fitted to the hollow shaft.

37. In a rotary printing press a hollow type-cylinder having a cylindrical body; an end-piece secured to the cylindrical body and provided with an axial hole; an end-disk secured to the cylindrical body and provided with an axial hole; bushings in the said holes; a retaining shoulder formed on the bushing in the hole of the disk; and end-piece rotatably mounted on the shoulder bushing and semi-cylindrical hubs formed on the end-pieces.

38. In a rotary printing-press a type-cylinder adapted to be mounted in a frame and having a body adapted to receive type; recessed ends on the cylinder adapted to receive the ends of a type retaining bar; and type having a printing character on one end, a body having two parallel sides, an approximately radial side, a reentrant side, and a projection on the end opposite the character end adapted to fit over the type-retaining bar.

39. In a rotary printing-press a type cylinder having a hollow cylindrical body adapted to receive the type; a type retaining bar; type having a character end, three sides approximately perpendicular to the plane of the character end and a side inclined to the plane of the character end; a

projection on the end of the type opposite to the character end, adapted to engage with the said retaining bar; hubs on the type cylinder pierced by axial holes.

- 5 40. In a rotary printing-press; the combination of a frame; bearings in a frame; portions of a hollow sectional shaft journaled in the bearings; feed-wheels mounted on the said portions; a hollow type cylinder
10 mounted on sections of a hollow shaft and carried by the feed-wheels; interlocking

hubs on the feed-wheels and type cylinder; and a locking-rod uniting the several sections of the hollow shaft.

In testimony whereof I have signed my 15 name to this specification in the presence of two subscribing witnesses.

EDWIN R. STORM.
